UNITED STATES PATENT OFFICE.

HARRY LE ROY EMERY, OF PEORIA, ILLINOIS, ASSIGNOR OF ONE-HALF TO EARL H. JEFFRIES, OF PEORIA, ILLINOIS.

EGG BEATER.

Application filed June 9, 1924. Serial No. 718,709.

To all whom it may concern:

Be it known that HARRY LE ROY EMERY, a citizen of the United States of America, residing at Peoria, in the county of Peoria 5 and State of Illinois, has invented certain new and useful Improvements in Egg Beaters, of which the following is a specification.

My invention relates to egg beaters.

10 My invention has special reference to egg beaters of the class wherein sets of concentrically arranged beater members are driven in opposed directions to the end through such concentric arrangement, the normal 15 width of the beater element may be reduced to the minimum and further to the end that through such concentric arrangement a high degree of efficiency is attained.

The invention has special reference to the 20 manner of mounting, relative fashioning and capability of relative adjustment of the beater elements, all of which matters will be more particularly pointed out in subsequent description.

25 Referring to the drawings,

Fig. 1 is a side elevation of the device shown in operative relationship with a cup.

30 Fig. 2 also shows a side elevation with a positioning of the driving gear mechanism 30 at right angles to that shown in Fig. 1.

Fig. 3 is a cross sectional view on the line 3—3 of Fig. 1.

35 Fig. 4 is a vertical sectional view through the verticle axis of the lower portion of the device.

Fig. 5 is a cross sectional view on the line 5—5 of Fig. 2, and

40 Fig. 6 shows in side elevation the beater elements and means of attaching the same to the driving elements.

I am aware that prior to the development of my invention, that substantially the same form of gearing and support therefore, have been used and similarly that concentrically 45 arranged separately, supported and oppositely driven beater elements were of public knowledge, and it is to the end of improving upon such known devices that the present invention is directed. For instance, we have aimed to improve the general mechanics in building, but specially the invention 50 is directed to relative arrangement and relative fashioning of beater elements adapted to effect relative deflection from one set of beater elements toward the other, to the end

of increasing agitation to the highest degree attainable, also the invention is directed to an axial adjustment if desired, of sets of beater elements and the capability of setting same with respect to their driving 60 supports, that relative expansion or contraction of the normal width of the beater elements may be effected. Finally the invention includes detailed combinations of parts, and the fashioning and general arrangement of the same as hereinafter more particularly described.

Referring to the drawings, 10 refers generally to a framing adapted to support working parts, said framing including a 70 hand hold portion 11, offset portions 12—13 and intermediate vertical framing member 14.

In associating working parts of the device with frame member 10, a vertically disposed 75 rod 15 is provided, the upper end of said rod being journaled in perforations in offset member 12 and the lower end partially in offset member 13, and finally within a sleeve shaft member hereinafter referred to, said 80 rod extending downwardly from said frame and terminating in an extended lug 16. Upon rod 15 is fixed gear member 17, from which said rod is driven. Upon rod 15 is sleeved a hollow shaft 18, which said shaft 85 is journaled in a member of offset framing part 13. To sleeve member 18 is fixed gear member 19 which serves as a driving means for said sleeve. 20 is a driving gear member supported upon the intermediate frame 90 member 14 of the general frame by means of nut and bolt elements generally referred to as 21, which said gear meshes with gear member 17 and 19. 22 is a hand hold member attached to gear 20. Through the arrangement of the gear members as indicated 95 a turning of gear 20 will effect opposite directions of movement of rod 15 and sleeve shaft 18.

Referring now particularly to the beater 100 elements 23 are bar members, capable of a small degree of radial expansibility when arranged and supported in the manner indicated in the several figures of the drawings, said bar members being generally fashioned as indicated in said drawings and provided with a vertical perforation at their intermediate crossing points to adapt them to be journaled upon the lower end of rod member 15. The upper ends of the bar 110

members are fixed to the flange portion of collar 24 as shown, said collar in turn being adjustably fixed to sleeve member 18 by means of wing nut 25, thereby adapting said collar to be adjusted into different vertical positions upon sleeve shaft 18 as may be desired. The position, however, always being such that the crossing intermediate portions of said bars are always held in resilient contact with lug member 16 on the lower end of rod 15. 24^a is a stop member on the lower end of sleeve 18 adapted to prevent collar member 24 being passed beyond the end of said sleeve member 18. The beater bars are fixed with respect to the driving sleeve member designedly to prevent lateral extension and resulting widening of the beater element under the influence of rotary action, but capable of adjustment to effect limited variable expansion and widening or narrowing of the beater element to suit the different uses of the same. 26 are beater bar members of the same or substantially the same general form as beater elements 23, the same being relatively arranged in substantially the same manner as said beater elements 23, but normally positioned (see Fig. 3) at different angularity than that of said beaters 23. Beater elements 26 are provided with a perforation at their crossing points for journaling in connection with the rod 15 and their upper ends are attached to the flange portion of a sleeve member 27, the latter being adjustably fixed to rod 15 by means of wing nut 28 to provide for the same adjustable fixing as heretofore described in connection with collar member 24. The relative spacing with respect to beater members 23 and 26 may be changed at will by merely effecting a proper relative spacing of collar members 24 and 27, thereby meeting variable conditions of general use of the device. A spacing washer 29 is adapted to be interposed at the cross-

ing point of the respective sets 23 and 26 of the beater members for the purpose of promoting efficiency as well as providing a better mechanical structure.

Special attention is directed to means provided for promoting agitation (see particularly Figs. 3 and 6) which consists in the matter of relative deflection or bending of the portions of the beater members intermediate their upper and lower supports. The outer sets of beater members 23 are turned at an angle as at 30 (see Figs. 3 and 6) from the line of travel of said members and similarly beater members 26 are turned at a similar angle as at 31, but in the opposite direction from the deflection of the outer beater members to the end that as said sets rotate in opposite directions a deflection of the materials will be effected, thereby promoting extreme agitation.

What I claim is:

1. In combination, concentrically arranged driving members, the end of the inner member extending beyond the outer member, a collar on each member, each collar being slidably adjustable on its respective member independent of the other, beater members fastened to said collars at one end and journaled at their other end on the inner driving member, whereby each beater may be expanded outwardly independent of the other, in order that the spacing between the oppositely rotating beater members may be varied.

2. A device as specified in claim 1 in which the beater members are composed of strips, said strips being at an angle to their respective paths of travel, the inclination of the angle of the strips of the inner beater being opposite to the inclination of the angle of the outer beater.

In testimony whereof I affix my signature.

HARRY LE ROY EMERY.
